United States Patent Office

Des. 207,777
Patented May 30, 1967

207,777

CHAIR

Robert E. Kjer Jakobsen, Los Angeles, Calif., assignor to Schlumberger Limited (Schlumberger N.V.), Houston, Tex., a corporation of the Netherlands Antilles

Filed June 9, 1966, Ser. No. 2,620

Term of patent 14 years

(Cl. D15—1)

I claim:

The ornamental design for a chair, substantially as shown.
